FUEL INJECTION SYSTEM

Robert J. Powell and James E. Champion, Muskegon, Mich., assignors to Continental Motors Corporation, Muskegon, Mich., a corporation of Virginia

Filed Nov. 13, 1958, Ser. No. 774,574

7 Claims. (Cl. 261—23)

This invention relates to continuous flow fuel injection systems for multi-cylinder internal combustion engines, and more particularly to an improved fuel injector nozzle construction adapted for use with continuous flow systems in multi-cylinder engines.

In the development of continuous flow fuel injection systems having fuel injection nozzles connected with the individual cylinder air intakes of the engine to provide a continuous injection of fuel under pressure various difficulties are encountered. At idle engine operation, the decreased manifold pressure tends to draw fuel from the pipes leading to the injection nozzles, as well as increasing the tendency of fuel to boil in the distribution lines due to the low pressure. Consequently, upon advancing the throttle, fuel is not immediately available at sufficient pressure to ensure the desired immediate engine response. Utilization of complex controls and nozzles to overcome this defect only serves to increase the cost of the system and increases the cost of maintenance and servicing. Also, it is found that with such systems, effective fuel atomization is difficult to achieve since the fuel travels a relatively short distance to the cylinder intake valve.

An object of the present invention is to improve performance of internal combustion engines utilizing fuel injection by providing a simplified and improved fuel injection nozzle construction.

Another object of the invention is to eliminate the aforesaid fuel line depletion of idling operation by constructing a fuel injection nozzle having an air inlet to the fuel discharge passage provided with a simplified duct shield.

A further object of the invention is to provide an improved fuel injection nozzle by constructing a casing having a fuel discharge passage vented to atmosphere and an individual removable fuel jet intake element.

Yet a further object of the invention is to improve continuous flow fuel injection system efficiency by providing an improved nozzle automatically operable to discharge an aerated fuel stream into the cylinder intake branch ducts.

For a more complete understanding of this invention, reference may be made to the accompanying drawings illustrating two preferred embodiments of the invention in which like reference characters refer to like parts throughout the several views, and in which

Fig. 1 is a diagrammatic representation of a preferred multi-cylinder internal combustion engine utilizing the present invention.

Fig. 2 is an elevational view partially in cross-section, illustrating one preferred type of fuel injection nozzle.

Fig. 3 is a nozzle end view of the injection nozzle of Fig. 2 as seen from the line 3—3.

Fig. 4 is a cross-sectional view taken substantially on the line 4—4 of Fig. 2.

Fig. 5 is an elevational view partially in cross-section, illustrating another preferred type of fuel injection nozzle.

2

Fig. 6 is a nozzle end view of the injection nozzle of Fig. 5 as seen from the line 6—6.

Fig. 7 is a cross-sectional view taken substantially on the line 7—7 of Fig. 5, and

Fig. 8 is a cross-sectional view taken substantially on the line 8—8 of Fig. 5.

A multi-cylinder internal combustion engine 10 is diagrammatically illustrated in Fig. 1 as having engine cylinders 11 provided with cylinder air intake structures or branch ducts 12. An air intake manifold structure 13 conducts air to the intake branch ducts 12 from a throttle intake structure 14 having an adjustable throttle air valve 15. In some engines, a conventional supercharger 16 may be included.

The continuous flow fuel injection system comprises a fuel tank 20, a fuel pump 21, a fuel injection metering valve 22 preferably controlled through linkage 23 from the throttle valve 15, and a fuel delivery manifold 24. Fuel pipes 25a, 25b and 25c preferably connect respectively the tank 20, the pump 21, the metering valve 22, and the fuel delivery manifold 24.

Fuel delivery lines 25 connect the fuel delivery manifold 24 with fuel injection nozzles 26 mounted on the cylinder air intake branch ducts 12 and adapted to inject fuel into the individual cylinder air intakes.

Figs. 5 through 8 illustrate a preferred nozzle 26, utilized in engines having the supercharger 16. Figs. 2 through 4 illustrate a preferred nozzle 27 utilized in engines not having the supercharger 16.

The nozzle 27 as seen in Figs. 2 through 4 comprises a casing structure 28 including a nozzle member 29 adapted for connection into the cylinder air intake 12. A discharge passage 30 extends longitudinally through the casing structure 28 and has an enlarged chamber portion 31 at its inner end. An individual fuel intake jet member 32 is screw threaded as at 33 into the chamber 31, and is provided with a smaller diameter portion 34 which, when disposed in the chamber 31 with its end closely adjacent the inner end of the passage 30, converts the chamber 31 into an elongated annular passage. A fuel jet intake passage 35 extends longitudinally through the member 32 and has a restricted jet passage 36 near its inner end. The end of the casing opposite the nozzle member 29 is threaded as at 37 for connection with the fuel line 25. The intake passage 35 is axially aligned with the discharge passage 30 so that a continuous flow of fuel, supplied under pressure from the fuel delivery manifold 24 will be injected directly through the passage 30 into the cylinder air intake branch duct 12.

The outer side of the casing 28 is provided with an annular recess 40, and is open to atmosphere. A plurality of radial passages 41 connect this recess 40 with the chamber 31.

In operation, when the engine is idling and manifold pressure drops below atmospheric pressure, instead of sucking fuel from the fuel intake passage 35 and the fuel line 25 connected to the casing 28, air will be drawn through the passages 41 and the chamber 31 into the fuel discharge passage 30.

For best operation, it has been found that the preferred total cross-sectional area of the passages 41 should be approximately four times the cross-sectional area of the fuel discharge passage 30 at its smallest point, and the diameter of the discharge passage 30 should be approximately 1½ to 2½ times the diameter of the smallest part of the fuel inlet passage 35; that is, the restricted jet passage 36. The fuel jet intake member 32 is readily removed for ease in cleaning the fuel injection nozzle 26.

Also, the passage 30 should be relatively long, preferably at least six to twelve times its diameter, to permit of fuel atomization therein, and is so constructed as to permit air flow through it less than normal idle air requirements, so as not to upset the normal functioning of the air induction system.

During engine idle operation, with low manifold pressures on the order of about 12" Hg the fuel flow reduced to a minimum, admission of air into the passages 41 at substantially atmospheric pressure supplies part of the idle air requirements of the engine. Inasmuch as the air flow through the passages 41 can more than satisfy the demands of the passage 30, the passage 36 remains at substantially atmospheric pressure, thus preventing the low manifold pressure from causing a boiling effect in the fuel lines or from drawing excess fuel into the cylinders. As engine power and manifold pressure are increased, fuel delivery is also increased. The moment fuel velocity from the passage 36 exceeds the free velocity in the passage 30, the fuel injected into the passage 30 produces a jet siphon effect, drawing in more air through the passages 41, due to a suction formed by the fuel passing from the passage 36 into the passage 30. This reduction of pressure drawing in air produces an atomization of the fuel in the relatively long discharge passage 30 prior to injection into the air induction manifold. In effect, continuously aerating the fuel stream augments induction air flow and facilitates easier and more rapid fuel vaporization than is possible where fuel is injected directly in a continuous stream into the manifold. The various cross-sectional areas of the fuel intake duct 36, the discharge passage 30, and the air intake passages 41 are predetermined by the size and requirements of the particular engine with which the nozzles are used, and cooperate to produce the continuous siphoning and atomization effects described above.

A cylindrical air cleaner screen 45 is arranged to be slipped over the casing 28 to entirely enclose the recess 40, and a cylindrical dust shield element 46 is disposed concentric with and spaced from the screen 45. The dust shield is open only at the one end, as at 47, which is farthest removed from the passages 41 opening from the recess 40 to provide a tortuous passage for the air.

The type of injection nozzle 27 may not be desirable with supercharged engines, because at engine speeds above idling, manifold pressure may rise above atmospheric pressure, causing fuel and air to be exhausted out the air inlet passages 41. For supercharged engines, therefore, a fuel injection nozzle 26 is preferably provided, as illustrated in Figs. 5 through 8.

In the nozzle 26, the casing structure 28, the nozzle member 29, the discharge passage 30, the chamber portion 31, the fuel intake jet member 32 having the smaller diameter portion 34, the fuel jet intake passage 35, the restricted jet passage 36, the annular recess 40, and the radial passages 41, are all identical in construction and operation with the like parts described in connection with the injection nozzle 27 of Figs. 2 through 4.

However, a second casing section 50 is disposed on the casing structure 28 to provide a closed annular air chamber 51. A check valve structure 52 is mounted on the casing section 50 and communicates with the air chamber 51 through a radially extending port 53. The check valve structure 52 comprises a ball check valve 54 adapted to be held against an annular seal 55 by a relatively weak spring 56.

Thus, in engine operation when manifold pressure exceeds atmospheric pressure due to supercharger operation, the ball check valve 54 will close to prevent discharge of air and fuel out of the passages 41, and when manifold pressure drops below atmospheric pressure, the ball check valve 54 will open to admit air to prevent excess fuel from being drawn through the intake passage 35 and to augment air flow by continuously aerating the fuel stream.

A cylindrical air cleaner screen 52 enclosing the check valve structure 52 and concentrically spaced therefrom is mounted on the casing section 50, and a cylindrical dust shield 58 is mounted on the screen 57 so that the open end, as at 59, is removed from the open end of the check valve structure 52, to provide a tortuous passage for the entering air.

Although we have described only two embodiments of the invention, it will be apparent to one skilled in the art to which the invention pertains that various changes and modifications may be made therein without departing from the spirit of the invention or the scope of the appended claims.

This application is a continuation-in-part of our co-pending application Serial No. 634,536, filed Jan. 16, 1957, for Fuel Injection System, now abandoned.

We claim:

1. In a continuous flow fuel injection system for a multi-cylinder internal combustion engine having a cylinder air intake and an air manifold structure provided with a throttle valve and branch ducts connecting said manifold with said cylinders, integral fuel injection nozzles each comprising a casing structure removably mounted on one of said air intake manifold branch ducts, said casing structure having a fuel discharge passage provided with an outer end port opening directly into said branch duct, a fuel jet member removably secured in said casing structure and having a fuel jet intake duct openly connected with the inner end of said fuel discharge passages, means supplying a continuous flow of liquid metered fuel under pressure to said fuel jet intake duct, said casing structure having an air inlet means connecting said discharge passage with atmosphere, said fuel jet intake duct and said fuel discharge passage cooperating when fuel pressure exceeds manifold air pressure to continuously siphon air from said air inlet means into said discharge passage by reason of fuel flow from said fuel jet intake duct into said discharge passage, and said fuel jet intake duct and fuel discharge passage being constructed and arranged to aerate the fuel stream within said fuel discharge passage.

2. In a continuous flow fuel injection system for a multi-cylinder internal combustion engine having a cylinder air intake and an air manifold structure provided with a throttle valve and branch ducts connecting said manifold with said cylinders, integral fuel injection nozzles each comprising a casing structure removably mounted on one of said air intake manifold branch ducts, said casing structure having a fuel discharge passage provided with an outer end port opening directly into said branch duct, a fuel jet member removably secured in said casing and having a fuel jet intake duct openly connected with the inner end of said fuel discharge passage, means supplying a continuous flow of liquid metered fuel under pressure to said fuel jet intake duct, said casing structure having an air inlet means connecting said discharge passage with atmosphere, said fuel jet intake duct and said fuel discharge passage cooperating when fuel pressure exceeds manifold air pressure to continuously siphon air from said air inlet means into said discharge passage by reason of fuel flow from said fuel jet intake duct into said discharge passage, and said fuel jet intake duct and fuel discharge passage being constructed and arranged to aerate the fuel stream within said fuel discharge passage, said fuel jet intake duct being axially aligned with said fuel discharge passage and provided with a restricted jet opening adjacent the end opening into said fuel discharge passage.

3. In a continuous flow fuel injection system for multi-cylinder internal combustion engines having a cylinder air intake and an air induction system including an air intake manifold structure provided with a throttle valve and branch ducts connecting said manifold with said cylinders, integral fuel injection nozzles each comprising a casing structure removably mounted on one of

said air intake manifold branch ducts and having a fuel discharge passage provided with an outer end port opening directly into said branch duct, said casing structure having an enlarged chamber openly connected with the inner end of said fuel discharge passage, a fuel jet member removably secured in said casing and extending into said chamber to form an annular space surrounding a portion of said fuel jet member, said fuel jet member having a fuel jet intake duct directly openly connected with said chamber adjacent and axially spaced from the inner end of said fuel discharge passage, means supplying a continuous flow of liquid metered fuel under pressure to said fuel jet intake duct, said casing structure having an air inlet means openly connecting said annular space with atmosphere, said fuel jet intake duct and said fuel discharge passage cooperating when fuel pressure exceeds manifold air pressure to continuously siphon air from said annular space into said discharge passage by reason of fuel flow from said fuel jet intake duct into said discharge passage at engine speeds above idling, said fuel jet intake duct and said fuel discharge passage being constructed and arranged to aerate the fuel stream within said discharge passage.

4. In a continuous flow fuel injection system for a multi-cylinder combustion engine having a cylinder air intake and an air induction system including valve and branch ducts connecting said manifold with said cylinders, integral fuel injection nozzles each comprising a casing structure removably mounted on one of said air intake manifold branch ducts and having a fuel discharge passage provided with an outer end port opening directly into said branch duct, said casing structure having an enlarged chamber openly connected with the inner end of said fuel discharge passage, a fuel jet member removably secured in said casing and extending into said chamber to form an annular space surrounding a portion of said fuel jet member, said fuel jet member having a fuel jet intake duct openly connected with said chamber adjacent and axially spaced from the inner end of said fuel discharge passage, means supplying a continuous flow of liquid metered fuel under pressure to said fuel jet intake duct, said casing structure having an air inlet means openly connecting said annular space with atmosphere, said fuel jet intake duct and said fuel discharge passage cooperating when fuel pressure exceeds manifold air pressure to continuously siphon air from said annular space into said discharge passage by reason of fuel flow from said fuel jet intake duct into said discharge passage at engine speeds above idling, said fuel jet intake duct and said fuel discharge passage being constructed and arranged to aerate the fuel stream within said discharge passage, said air inlet means comprising an air passage openly connected to atmosphere and to said annular space at a location upstream of said fuel jet intake duct connection with said chamber.

5. In a continuous flow fuel injection system for a multi-cylinder combustion engine having a cylinder air intake and an air induction system including valve and branch ducts connecting said manifold with said cylinders, integral fuel injection nozzles each comprising a casing structure removably mounted on one of said air intake manifold branch ducts and having a fuel discharge passage provided with an outer end port opening directly into said branch duct, said casing structure having an enlarged chamber openly connected with the inner end of said fuel discharge passage, a fuel jet member removably secured in said casing and extending into said chamber to form an annular space surrounding a portion of said fuel jet member, said fuel jet member having a fuel jet intake duct openly connected with said chamber adjacent and axially spaced from the inner end of said fuel discharge passage, means supplying a continuous flow of liquid metered fuel under pressure to said fuel jet intake duct, said casing structure having an air inlet means openly connecting said annular space with atmosphere, said fuel jet intake duct and said fuel

discharge passage cooperating when fuel pressure exceeds manifold air pressure to continuously siphon air from said annular space into said discharge passage by reason of fuel flow from said fuel jet intake duct into said discharge passage at engine speeds above idling, said fuel jet intake duct and said fuel discharge passage being constructed and arranged to aerate the fuel stream within said discharge passage, said air inlet means comprising an air passage openly connected to atmosphere and to said annular space at a location upstream of said fuel jet intake duct connection with said chamber, said casing structure having an exterior annular air recess openly connected with said air passage, a screen element enclosing said air recess, and a dust shield element partially enclosing said screen element and constructed to provide a tortuous path for air entering said air passage.

6. In a continuous flow fuel injection system for a multi-cylinder internal combustion engine having a cylinder air intake and an air induction system including an air intake manifold structure provided with a throttle valve and branch ducts connecting said manifold with said cylinders, integral fuel injection nozzles each comprising a casing structure removably mounted on one of said air intake manifold branch ducts and having a fuel discharge passage provided with an outer end port opening directly into said branch duct, said casing having an enlarged chamber openly connected with the inner end of said fuel discharge passage, a fuel jet member removably secured in said casing and extending into said chamber to form an annular space surrounding a portion of said fuel jet member, said fuel jet member having a fuel jet intake duct openly connected with said chamber adjacent and axially spaced from the inner end of said fuel discharge passage, means supplying a continuous flow of liquid metered fuel under pressure to said fuel jet intake duct, a casing structure having an air inlet means openly connecting said annular space with atmosphere, said fuel jet intake duct and said fuel discharge passage cooperating when fuel pressure exceeds manifold air pressure to continuously siphon air from said annular space into said discharge passage by reason of fuel flow from said fuel jet intake duct into said discharge passage at engine speeds above idling, said fuel jet intake duct and said fuel discharge passage being constructed and arranged to aerate the fuel stream within said discharge passage, said casing structure having an exterior annular air recess, said air inlet means comprising a plurality of air inlet passages extending radially from said annular space to one end of said exterior air recess, a screen element enclosing said recess and radially spaced therefrom, and a dust shield element radially spaced from and partially enclosing said screen element, said dust shield element having an air inlet opening adjacent the other end of said air recess and offset from said air inlet passages to provide a tortuous path for air entering same.

7. In a continuous flow fuel injection system for a multi-cylinder internal combustion engine having a cylinder air intake and an air induction system including an air intake manifold structure provided with a throttle valve and branch ducts connecting said manifold with said cylinders, integral fuel injection nozzles each comprising an elongated casing structure removably mounted on one of said air intake manifold branch ducts and having an elongated fuel discharge passage provided with an outer end port opening directly into said branch duct, the length of said discharge passage being approximately six to twelve times the diameter thereof, said casing structure having an enlarged bore axially aligned with said discharge passage and having the inner end openly connected with the inner end of said discharge passage, and a separate fuel jet member removably secured in said bore and having an inner reduced diameter portion of smaller diameter than said bore to provide an elongated inner annular space connecting with the inner end of

7
said discharge passage, said fuel jet member having an axially extending fuel intake passage therethrough provided with a restricted venturi jet opening at the inner end, and said casing structure having an air inlet means connecting the elongated annular space with atmosphere, means supplying a continuous flow of liquid metered fuel under pressure to said fuel jet member, said venturi jet opening and said fuel discharge passage cooperating when fuel pressure exceeds manifold air pressure to siphon air from said annular space into said discharge 10 passage by reason of fuel flow from said venturi jet opening into said discharge passage at engine speeds above idling, said venturi jet opening and said fuel dis-

5
charge passage being constructed and arranged to aerate the fuel stream within said fuel discharge passage.
